CLAIM

The ornamental design for an ergonomic pet comb handle, as shown and described.

DESCRIPTION

FIG. 1 is a front perspective view of an ergonomic pet comb handle according to my new design;

FIG. 2 is a top plan view thereof;

FIG. 3 is a bottom plan view thereof;

FIG. 4 is a left side view thereof;

FIG. 5 is a right side view thereof;

FIG. 6 is a front view thereof; and,

FIG. 7 is a back view thereof.

The broken lines and unshaded portions contained within broken lines depict unclaimed features of the ergonomic pet comb handle that form no part of the claimed design but are shown for purposes of illustration.

1 Claim, 6 Drawing Sheets
